E. Faron,

Link Motion for Slide Valves.

No. 96,903.

Patented Nov. 16, 1869.

E. Faron
By his Atty
H. Howson

United States Patent Office.

EDWARD FARON, OF CHESTER, PENNSYLVANIA, ASSIGNOR TO REANEY, SON & CO., OF SAME PLACE.

Letters Patent No. 96,903, dated November 16, 1869.

IMPROVED LINK-MOTION DEVICE FOR STEAM-ENGINES.

The Schedule referred to in these Letters Patent and making part of the same.

To all whom it may concern:

Be it known that I, EDWARD FARON, of Chester, county of Delaware, State of Pennsylvania, have invented an Improved Link-Motion for Slide-Valves; and I do hereby declare the following to be a full, clear, and exact description of the same.

My invention consists of a link-motion constructed in the peculiar manner, fully described hereafter, with the view of attaining the important qualities of general steadiness and compactness, simplicity, and economy, as regards construction.

In order to enable others familiar with machinery of this class to make and apply my invention, I will now proceed to describe its construction and operation, reference being had to the accompanying drawing, which forms a part of this specification, and in which—

Figure 1 is a front view of my improved link-motion for slide-valves;

Figure 2, a vertical section on the line 1-2, fig. 1; and

Figure 3, a plan view of the link.

Similar letters refer to similar parts throughout the several views.

A is the link, consisting of a solid bar forming the segment of a ring, the radius of which is determined in the usual manner, well known to engineers.

Near each end of the link is a pin, *a*, each pin receiving the end of an eccentric rod, as shown by dotted lines in fig. 1, and the link is arranged to fit snugly but slide freely in a disk which has lips *b* overlapping the link, as shown in fig. 2.

To the rear of the disk is secured, by riveting, or otherwise, a steel plate, *d*, and both disk and plate fit so as to turn freely in a recess in the cross-head *D*, to which the steel plate is held by a pin, *E*, and its nut *c*, the said pin being concentric with the disk.

In front of the link is a pin, *F*, for receiving the ends of a rod, *G*, shown by dotted lines, fig. 1, the said rod being connected to the starting-lever, or other starting and stopping-appliances.

The valve-rod *H* is secured to the projection *h* of

the cross-head *D*, and a guide-rod, *j*, to another projection, *i*, on the same cross-head.

It will be unnecessary to describe here the method of operating the link, or the action of the same on the valve as regards altering the stroke of the same and reversing or stopping its movements, inasmuch as the link is caused to perform precisely the same duties as those in common use. It will suffice to remark as regards the operation of my link-motion, that as the disk *b* is free to oscillate in the cross-head, it will accommodate itself to all the varying movements of the link.

It is the peculiar construction of the link-motion to which my invention especially relates, and the peculiarities may be referred to as follows:

The link, instead of being open, as usual, consists of a simple solid bar. The importance of this feature as regards economy in construction, will be readily understood by engineers without explanation.

The link passing through the disk, which affords a lengthened bearing, and the disk being embedded in a recess of the guided cross-head, the qualities of general steadiness and durability as regards wear and tear are attained, to which may be added, as other qualities of importance, general compactness and simplicity of parts.

I claim as my invention, and desire to secure by Letters Patent—

1. A solid link, *A*, arranged to slide in a disk, *b*, which is adapted to, and can oscillate in the cross-head of a valve-spindle, substantially as set forth.

2. The plate *d*, interposed between the disk *b* and the cross-head, and held to the latter by a pin, *E*, concentric with the said disk, all substantially as set forth.

In testimony whereof, I have signed my name to this specification, in the presence of two subscribing witnesses.

Witnesses: EDWARD FARON.
JOHN LONGBOOTHAM,
SAMUEL ULRICH.
